US00D496994S1

(12) **United States Design Patent** (10) Patent No.: **US D496,994 S**
Tague et al. (45) Date of Patent: **** Oct. 5, 2004**

(54) **COMBINED MONOMER CRACKER AND TOOL**

4,570,838 A * 2/1986 Szemere et al. 225/93
D291,489 S * 8/1987 Dudnyk D24/127

(75) Inventors: **Christopher M. Tague**, Portage, MI (US); **Kris D. Eager**, Richland, MI (US)

* cited by examiner

Primary Examiner—Holly Baynham

(74) Attorney, Agent, or Firm—Howard & Howard

(73) Assignee: **Stryker Instruments**, Kalamazoo, MI (US)

(57) **CLAIM**

We claim the ornamental design for a combined monomer cracker and tool, as shown.

DESCRIPTION

FIG. 1 is a perspective view of a combined monomer cracker and tool;

FIG. 2 is a side view of the combined monomer cracker and tool, both sides being identical;

FIG. 3 is a top view of the combined monomer cracker and tool;

FIG. 4 is a bottom view of the combined monomer cracker and tool;

FIG. 5 is an end view taken from the left end of FIG. 2; and, FIG. 6 is an end view taken from the right end of FIG. 2.

(***) Term: **14 Years**

(21) Appl. No.: **29/169,599**

(22) Filed: **Oct. 23, 2002**

(51) LOC (7) Cl. **24-02**

(52) U.S. Cl. **D24/133**
